UNITED STATES PATENT OFFICE.

CHARLEY FREDRICK STEGMEIER, OF WAUNA, OREGON.

RAILWAY-MAIL-TRANSFER APPARATUS.

1,413,297.

Specification of Letters Patent. Patented Apr. 18, 1922.

Application filed June 8, 1920. Serial No. 387,328.

To all whom it may concern:

Be it known that I, CHARLEY FREDRICK STEGMEIER, a citizen of Switzerland, and a resident of Wauna, in the county of Clatsop and State of Oregon, have invented certain new and useful Improvements in Railway-Mail-Transfer Apparatus, of which the following is a specification:

This invention relates generally to apparatus for delivering and receiving mail bags or the like to and from railway vehicles, and is especially adapted for handling the mail between the railway vehicles and the stations along the railway line.

The object of the invention is to provide a device of this character which is of simple and durable construction and reliable in operation, serving to easily and readily effect the transfer of the mail bags to and from the railway vehicle in one operation and which is especially adapted to be automatically operated so as to require no human control or manipulation with respect to the various phases of this operation.

Other objects and advantages of the invention reside in certain novel features of construction, combination and arrangement of parts which will be hereinafter more fully described and particularly pointed out in the appended claims, reference being had to the accompanying drawings forming part thereof, and in which:

Figure 1 is a transverse sectional view of the apparatus in operative position;

Figure 2 is a similar view of the device carried by the car showing the parts in non-extended and inoperative position;

Figure 3 is a sectional view on line 3—3 of Figure 1, looking in the direction of the arrows;

Figure 4 is a side elevational view of the vehicle showing the car immediately prior to the engagement of the operating lever with the depressor and immediately after the engagement of the operating lever with the depressor;

Figure 5 is a fragmentary side elevational view of the extendible carriage;

Figure 6 is a transverse sectional view thereof;

Figure 7 is a detail perspective view of the device carried by the car; and

Figure 8 is a diagrammatic view, illustrating the cooperative action of the receiver and supports of the vehicle and of the ground.

Referring to the drawings, wherein for the sake of illustration there is shown a preferred embodiment of the invention, it will be seen that the railway vehicle is indicated at A and includes a car rig or device indicated generally at B which is adapted to successively cooperate with land rigs or co-operating device C to effect a transfer of the mail bags or the like D to and from the railway vehicle.

The adjacent side wall of the vehicle is provided with a suitable opening 10 and the upper rail 11 of a track extends from the side wall immediately above the opening 70 transversely across the car to the opposite wall. This rail is secured in position by engagement with the side wall and also by hangers 12 which depend from the top wall of the car or vehicle. A lower rail 13 is arranged below the upper rail 11 and in vertical alinement therewith, and is also suspended by hangers 12 as clearly shown in Figures 6 and 7. Each of the rails 11 and 13 comprises a channel member, the channel 75 member comprising the upper rail 11 being inverted. A third rail 14 is arranged parallel to and intermediate the rail 11 and 13 and is provided with a T-slot 15 extending throughout its entire length.

An extendible carriage, indicated generally at 16, is operatively mounted upon the track. The carriage preferably embodies a lazy tongs construction and consists of a series of angularly arranged levers 17 pivoted together in the middle, as shown at 18, and at their ends, as shown at 19. The end levers are of such length as to terminate at the middle pivot, as shown at 20. A stud 21 having a T-head 22 which operates in 95 the T-slot of the third rail 14 is carried by

each of the pivots 18 and is preferably formed integral with these pivots. The action of the third rail or guide rail 14 is thus to constrain the carriage to rectilinear extension. A cross head 23 has spaced lugs 24 formed thereon which embrace and pivotally secure the outer end pivot 20 of the extensible carriage. The ends of the cross head 23 are extended laterally, as at 25, and operate in the channel of the members 11 and 13. The rear or inner end of the carriage is secured by the pivot 20 to a block 26 which is positively secured to the stationary structure of the car, as indicated in Figure 1.

A bracket 27 is secured to and carried by the cross head 23. This bracket includes an upper laterally extending arm 28 and a lower laterally extending arm 29, which carry, respectively, the receiver 30 and the support 31. The arms 28 and 29 are adapted to be projected through the opening 10 in the side wall of the vehicle in order to position the receiver and support in operative relation with respect to the receiver and support carried by the ground.

The device carried by the ground includes a suitable post having a laterally extending upper arm 32 and a laterally extending lower arm 33, the upper arm 32 carrying the support 34 and the lower arm 33 carrying the receiver 35. Each of these arms is provided with an offset 36 to permit free passage of the door 37 for the closure 10 of the car in the event it is desired to carry this door at the end of the lateral arm.

The upper arm 28 of the device carried by the car has a pair of receiver forks 38 arranged at its outer end. The receiver forks 38 are spaced from each other and are adapted to operate between the spaced forks 39 of the support 34. The lower arm 29 of the device carried by the car carries at its outer end a pair of spaced forks 40 constituting the supports 31 which are adapted to operate between a pair of spaced receiver forks 41. As clearly shown in Figures 3 and 7, the forks of both the receiver and the support consist of a pair of legs 42, the outer ends of which are flared outwardly, as shown at 43. These forks are carried on the outer ends of offsets 44 and are preferably slightly upwardly inclined. As clearly shown in Figures 3 and 8 the receiver forks 38 which are carried by the upper arm 28 of the bracket 27 have their open ends extending in the direction of motion of the car. The forks 39 of the support 34 of the ground rig have their open ends extending in the same direction. The forks 38 and the forks 39 are arranged in substantially the same horizontal plane but the forks 39 are spaced such a distance apart that the forks 38 pass between them. The forks 40 of the support 55 of the car rig have their open ends extend-

ing in a direction opposite to the direction of motion. In other words, these forks extend in a direction opposite to the direction in which the receiver forks 38 extend. The receiver forks 41 of the ground rig have 70 their open end extending in the same direction as the forks 40. These receiver forks 41 and the forks 40 of the support are arranged to lie in substantially the same horizontal plane but the receiving forks 41 are 75 arranged such a distance apart that the forks 40 pass between them. As indicated in Figures 1, 3 and 8 the mail bag or similar element D is provided with laterally extending trunnions 45 which are elongated 80 and adapted to rest in the crotch of the forks of the car rig or of the land rig or of both.

Means are provided for automatically projecting the receiver and support of the railway vehicle into position to enter into co-operative action with the receiver and support of the ground. This means comprises a lever 46 fulcrumed at 47 to the inner face of the side wall of the car. The upper end of the lever operates in a slot 48 provided 90 in the car and the extremity of this upper end carries a roller 49. A connecting element 50 such as a cable, rope or the like extends over and between suitable guide pulleys 51 to the extensible carriage and is fastened to one of the pivots 18 of the carriage, as indicated at 52. A stationary depressor 53 consisting of an inverted channel member is adapted to cooperate with the lever to depress or swing the same about its 100 fulcrum 47, the motion of the lever being transmitted through the connecting element 50 to the extensible carriage to project the bracket. This depressor 53 is carried by a lateral extension 51' of a spaced post 54 105 which may also carry the land rig or device carried by the ground.

The extensible carriage is automatically retracted when the lever no longer engages the depressor and the means for this purpose 110 comprises a weight 56 mounted for operative movement in the box 57 and normally retracting the extensible carriage by means of the connecting element 58, such as a cable or cord which has one end attached to the 115 weight 56 and its opposite end attached to one of the middle pivots 18 of the carriage, as shown at 52. This connection at 52 is the common connection for the connecting element from the weight and the connecting element from the lever.

In practice, as the vehicle approaches the point at which it is desired to transfer the mail, the lever 49 which normally occupies a vertical position, as seen to the left in Figure 4, is engaged by the depressor and swung to the position shown to the right in Figure 4. The motion of the lower end of the lever—transmitted through the connecting element 51—serves to extend the carriage, 125 130

thereby projecting the receiver and support of the car which is then in position to enter into cooperative action with the receiver and support of the ground rig. The forks of the receiver and support of the car pass between the forks of the receiver and support of the ground and the trunnions of the mail bag which then rest in the crotch of the forks 39 of the support of the ground rig are engaged by the forks 38 of the receiver of the car rig. Similarly the trunnions of the mail bag which rest in the crotch of the forks 40 of the support of the car are engaged by the forks 41 of the support of the ground rig. This cooperative action of the forks which results in the transfer of the mail bag is illustrated in Figure 3 and in the diagram in Figure 8. During the interval of this cooperative action the lever is maintained in the position shown to the right in Figure 4 by the depressor and it is not until the transfer is completed that the lever is freed from the action of the depressor to permit the weight 56 to automatically return the carriage to normal position shown in Figure 2; to bring the receiver and support of the car within the car.

The working parts may be isolated by the wall 59. It is to be noted that these working parts being disposed largely in the upper part of the car permit of the normal working space of the car to be utilized for various purposes.

Having thus described my invention, I claim:

1. An apparatus for transferring mail to and from railway vehicles comprising a device carried upon the railway car including an extendible carriage, a receiver and support carried by the extendible carriage, a device arranged upon the ground including a cooperating receiver and support, means for projecting the receiver and support of the device carried by the railway car into position to enter into cooperative relation with the receiver and support of the device arranged upon the ground and including a stationary depressor, a lever actuated by the depressor and means for transmitting the motion of the lever to the extendible carriage, and means for retracting the extendible carriage immediately subsequent to the engagement of the lever with the depressor.
2. An apparatus for transferring mail to and from railway vehicles comprising a device carried upon the railway car including an extendible carriage, a receiver and support carried by the extendible carriage, a device arranged upon the ground including a cooperating receiver and support, means for projecting the receiver and support of the device carried by the railway car into position to enter into cooperative relation with the receiver and support of the device

arranged upon the ground and including a stationary depressor, and a lever actuated by the depressor, and means for transmitting the motion of the lever to the extendible carriage.

3. An apparatus for transferring mail to and from railway vehicles comprising a device carried upon the railway car including a receiver and a support normally disposed within the car, a device arranged upon the ground and including a cooperating receiver and support, and means for projecting the receiver and support of the device carried by the railway car into position to enter into cooperative relation with the receiver and support of the device arranged upon the ground and including a stationary depressor, a lever fulcrumed to the car, and means for transmitting the motion of the lever to the receiver and support of the device carried by the railway car.

4. An apparatus for transferring mail to and from railway vehicles comprising devices partaking bodily of motion with respect to each other, each of which include a receiver and a support, the receiver of one device being adapted to cooperate with the support of the other device and the support of the first named device with the receiver of the second named device, one of said devices including an extendible carriage carrying the receiver and support thereof, means for extending the carriage to project the receiver and support into operative position including a lever carried by the device, and a depressor plate associated with the other of said devices, and means for retracting the receiver and support.

5. An apparatus for transferring mail to and from railway vehicles comprising devices partaking bodily of motion with respect to each other, each of which includes a receiver and a support, the receiver of one device being adapted to cooperate with the support of the other device and the support of the first-named device with the receiver of the second named device, one of said devices including an extendible carriage carrying the receiver and support thereof, means for extending the carriage to project the receiver and support into operative position including a lever carried by the device, and a depressor plate associated with the other of said devices.

6. An apparatus for transferring mail to and from railway vehicles comprising an extendible carriage consisting of a series of angularly arranged levers pivoted together in the middle and at their ends, a receiver connected to the carriage, a support connected to the carriage, means for extending the carriage to project the receiver and support into operative position, and means for retracting the carriage and normally retaining the same retracted to retain the re-

ceiver and support in non-operative position.

7. An apparatus for transferring mail to and from railway vehicles comprising an extendible carriage consisting of a series of angularly arranged levers pivoted together in the middle and at their ends, a receiver connected to the carriage, a support connected to the carriage, and means for extending the carriage to project the receiver and support into operative position.

8. An apparatus for transferring mail to and from railway vehicles comprising an extendible carriage consisting of a series of angularly arranged levers pivoted together in the middle and at their ends, and a receiver connected to the carriage, and a support connected to the carriage.

9. An apparatus for transferring mail to and from railway vehicles including an extendible carriage, a track for said carriage, a stationary block to which one end of the carriage is pivotally secured, a crosshead connected to the carriage and slidably mounted in the track, a bracket connected to the carriage and including an upper and a lower arm, a receiver carried by one of said arms, and a support carried by the other of said arms.

10. An apparatus for transferring mail to and from railway vehicles including an extendible carriage, a track for said carriage, a stationary block to which one end of the carriage is pivotally secured, a crosshead connected to the carriage and slidably mounted in the track, a bracket connected to the carriage and including an upper and a lower arm, a receiver carried by one of said arms, a support carried by the other of said arms, and means for extending the carriage to project the receiver and support into operative position.

11. An apparatus for transferring mail to and from railway vehicles including an extendible carriage, a track for said carriage, a stationary block to which one end of the carriage is pivotally secured, a crosshead connected to the carriage and slidably mounted in the track, a bracket connected to the carriage and including an upper and a lower arm, a receiver carried by one of said arms, a support carried by the other of said arms, means for extending the carriage to project the receiver and support into operative position, and means for normally retaining the carriage in retracted position to maintain the receiver and support in non-operative position.

12. An apparatus for transferring mail to and from railway vehicles including an extendible carriage, a track for said carriage consisting of an upper and lower channel member, a block rigidly connected to the track and to which one end of the carriage is pivotally secured, a crosshead connected

to the carriage and operating in the channel members, a bracket connected to the carriage and including an upper and lower arm, a receiver carried by one of said arms, a support carried by the other of said arms, means for extending the carriage to project the receiver and support into operative position, and means for normally retaining the carriage in retracted position to maintain the receiver and support in non-operative position.

13. An apparatus for transferring mail to and from railway vehicles including an extendible carriage consisting of a series of angularly arranged levers pivoted together in the middle and at their ends, a track for said carriage consisting of an upper and lower channel member, a block rigidly secured to the inner end of said track to which the inner end of the extendible carriage is pivotally connected, a crosshead pivotally connected to the outer end of said carriage and slidably mounted in the channel members of the track, means for guiding the carriage in its operative movements including a guide rail having a T-slot and a stud projecting from the carriage and having a T-head slidably arranged in the T-slot of the guide rail, a bracket connected to the carriage and including an upper and lower arm, a receiver carried by one of said arms and a support carried by the other of said arms.

14. An apparatus for transferring mail to and from railway vehicles including a carriage, a track for said carriage consisting of an upper and lower channel member, a cross head connected to the carriage and operating in the channel members, means for guiding the carriage in its operative movements, a bracket connected to the carriage and including an upper and lower arm, a receiver carried by one of said arms and a support carried by the other of said arms.

15. An apparatus for transferring mail to and from railway vehicles comprising an extendible carriage consisting of a series of angularly arranged levers pivoted together in the middle and at their ends, means for guiding the carriage in its operative movements including a guideway having a T-slot therein and a stud projecting from the carriage having a T-head slidably arranged in the T-slot in the guideway, a receiver connected to the carriage and a support connected to the carriage.

16. An apparatus for transferring mail to and from railway vehicles comprising a device carried by the vehicle including upper and lower arms, a receiver carried by the upper arm of the vehicle consisting of a fork having its open end extending in one direction, a support carried by the lower arm and consisting of a fork having its open end extending in the opposite direc-

tion from the fork of the receiver and a device carried by the ground including an upper arm, a lower arm, a support carried by the upper arm consisting of a fork having its open end extending in the same direction as the receiver of the car, and a receiver carried by the lower arm consisting of a fork having its open end extending in the same direction as the support of the device 5 carried by the car.

17. An apparatus for transferring mail

bags to and from railway vehicles comprising a receiver consisting of a fork having its open end extending in one direction and adapted to directly engage the mail bag, 15 and a cooperating support consisting of a fork having its open end extending in the same direction as the fork of the receiver and adapted to directly cooperate with said receiver fork.

CHARLEY FREDRICK STEGMEIER.
